SEWING MACHINE SUPPORTING CABINET
WITH COLUMN STAND

William A. Davidson, Elizabeth, N. J., assignor to
The Singer Manufacturing Company, Eliza-
beth, N. J., a corporation of New Jersey

Application November 21, 1945, Serial No. 629,960

1 Claim. (Cl. 312—239)

1

This invention relates to sewing machines and more particularly to sewing cabinets, tables or stands for supporting a family type sewing machine.

A primary object of the invention is to provide an improved sewing cabinet or table comprising a useful piece of furniture and adapted for convenient employment as a sewing machine supporting table affording ample leg-room for the sewing machine operator.

Another object of the invention is to provide a new and improved family type sewing machine cabinet or table in which the various parts are arranged for optimum convenience and utility.

Other important objects of the invention will be apparent from the following detailed description and appended claim and a preferred embodiment of the invention is illustrated in the accompanying drawing, wherein:

Fig. 1 is a perspective view of a table supporting a family type sewing machine; the extension leaf of the table being shown in open position.

Fig. 2 is a sectional view of the table shown with the sewing machine removed and the extension leaf closed. The section is taken on a vertical plane passed through the center line of the stand and extending from front to rear.

Fig. 3 is a horizontal sectional view of the table taken along the line 3—3 of Fig. 2 and looking in the direction of the arrows.

Fig. 4 is an enlarged vertical sectional view showing a portion of the lower drawer stopped in the position indicated by the dotted line of Figs. 2 and 3.

Referring to the drawing, the invention has been shown in Figs. 1 to 4 inclusive, as applied to a sewing machine table comprising a pedestal or base 10, supported on a plurality of feet 11; one of the said feet being located at each of the four corners of the pedestal. As illustrated in the drawing, the top wall of the pedestal 10 is spaced vertically from the feet 11, and the front portion of said top wall is cut away to provide a U-shaped recess 12 of substantial depth. The recess 12 divides the pedestal into left and right forwardly extending leg-extremities 13 and 14, respectively, and a rearwardly positioned top-wall section 16. By reason of the spacing of the wall-section 16 above the lower edges of the pedestal side walls 13 and 14, and the provision of the recess 12 in the wall-section 16, the pedestal 10 is U-shaped both horizontally and vertically.

The lower end of a hollow column 17 rests upon the upper surface of the main supporting section 16, medianly of the width of the top-wall

section, and is held thereon partly by fillets 18. The upper end of the said column 17 supports a lower cross member 19 (Fig. 2) comprising the bottom wall of a forwardly overhanging hollow table-head 21. The table-head includes right and left upstanding side boards 22 and 23, respectively, and an upstanding back board 24, the lower ends of which are secured to and supported from edges of the said member 19. A table-head top 26 overlies and is secured upon the uppermost edges of the three board members 22, 23 and 24 by a means not illustrated but well known in the art. A folding extension leaf 25 is hinged to the left side of the table-head top 15 26 in a known manner.

The table-head top 26 is provided with an aperture 27 for receiving the bed-plate of a portable family-type sewing machine 28. Communicating with and extending from the right side (Fig. 1) 20 of the aperture 27, is a small aperture 29 for accommodating electric extension cords 31 and 32, that respectively supply power to and control a small electric motor 33 associated with the sewing machine 28. The cord 31 extends to a source 25 of electric power (not shown) and the cord 32 is connected to a known type of foot controller 34, that may rest on the floor at a point intermediate the extremities 13 and 14. A pair of brackets 36 (only one of which is shown), depending from the top 26, are located to support the sewing machine bed 37 at a proper elevation in the aperture 27. A plurality of clips 38 carried by the brackets 36 engage opposite ends of the base of the portable sewing machine and thereby hold the sewing machine in the aperture 27. Each clip 38 is formed from an L-shaped piece of spring steel, having a horizontally extending arm secured to one of the brackets 36, and having an upstanding or vertical arm which carries a cork friction pad on the face adjacent the sewing machine bed 37. When the sewing machine is in place, the cork friction pads are resiliently pressed against the ends of the sewing machine bed 37, thus holding the sewing machine in proper position within the aperture 27. It will be understood that the sewing machine 28 is removed from the aperture 27 before the leaf 25 is moved from the open position shown in Fig. 1, to the closed position shown in Fig. 2. Since the machine 28 is only held in place by the friction provided by the spring clips 38, removal of the machine from engagement with the clips 38 is accomplished simply by lifting the machine upwardly.

55 A header 39, secured to the under side of the

table-head top 26 and held between the two side boards 22 and 23, reinforces the table-head and provides a stop for a front panel 41 of an upper drawer 42. A cross member 43, spaced below the table-head top 26 a distance equal to the height of the front panel 41, is secured between the two side boards 22 and 23. The drawer 42 extends from the front of the table-head to within a short distance of the back board 24, and is mounted to slide on cleats secured to the side walls 22-23, one of these cleats being shown in Fig. 2.

A lower drawer 44 is mounted to slide in the table-head 21 in a position below the drawer 42 and the cross member 43. In this connection, it should be noted that the bottom of the cross member 43 is spaced above the lower face of the bottom wall 19 a distance equal to the height of a front panel 45 of the drawer 44. Thus the drawer 44 is positioned to slide between lower portions of the side boards 22 and 23. The drawer 44 is approximately three-quarters as long as the upper drawer 42 and substantially shorter than the horizontal length of the side boards 22 and 23. The drawer 44 can be stopped in either of two closed positions. One of these, the repressed position, is shown by solid lines in Figs. 2 and 3 and the other normally closed position is shown by dotted lines in the same figures. As best shown in Fig. 4, a means has been provided for stopping the drawer 44 in the normally closed position. This includes a recessed plate 46, carried by the lower edge of the rear end board 47 of the drawer 44. A plunger 48, which is spring biased upwardly, is held by means of a flanged cylinder 49 in a bore 51 provided in the member 19. The lower drawer 44 is provided with a grooved block 52 supported on the bottom board 53 for holding scissors and other implements.

From the above, it will be apparent that many advantages are gained by constructing the sewing machine table in the manner shown. In the first place, the U-shaped recess 12, in the pedestal 10, provides space for the feet of an operator and also provides a convenient place for the foot controller 34. In the second place, the forwardly overhanging table-head 21 places the sewing machine 28 in a forward position convenient to the operator. In the third place, the short drawer 44, that can be repressed to the position shown in

Figs. 2 and 3, provides ample space for the knees of the operator. These features combine to provide a sewing machine table that has optimum convenience and utility. In normal use of the table as a piece of furniture, the drawer 44 is disposed in its forward position located by the stop-plunger 48, thereby improving the appearance of the table.

Having thus set forth the nature of the invention, what I claim herein is:

A sewing cabinet adapted for use in supporting a sewing machine having, in combination, a base including a top wall and laterally spaced side walls, said top wall being spaced a substantial distance above the lower edges of said side walls and having the front portion thereof cut away to provide a forwardly-open U-shaped clearance recess, said clearance providing space for the feet of an operator, a supporting column rising from 20 said top wall of said base substantially medially between the side walls thereof, a box-like sewing-cabinet-head supported by the upper end of said column and overhanging said forwardly-open U-shaped clearance recess, a substantially full-length forwardly opening upper drawer slidably mounted in said cabinet-head, a forwardly opening lower drawer slidably mounted in said cabinet-head, said lower drawer being shorter from front to rear than said upper drawer and being 30 capable of being pushed farther into said cabinet head than said upper drawer, thereby providing a knee receiving recess, and a stop-plunger mounted on the cabinet-head and contacting a portion of said lower drawer to 35 releasably hold the lower drawer with its front face in substantially vertical alignment with the front face of the upper drawer in the closed position of the latter.
